(No Model.)

W. P. GRANNIS.
DRAFT EQUALIZER.

No. 293,008.

Patented Feb. 5, 1884.

UNITED STATES PATENT OFFICE.

WILLIAM P. GRANNIS, OF WOLCOTTVILLE, INDIANA.

DRAFT-EQUALIZER.

SPECIFICATION forming part of Letters Patent No. 293,008, dated February 5, 1884.

Application filed September 19, 1883. (No model.)

To all whom it may concern:

Be it known that I, WILLIAM P. GRANNIS, a citizen of the United States, and a resident of Wolcottville, in the county of La Grange and State of Indiana, have invented certain new and useful Improvements in Draft-Equalizers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved draft-equalizer, showing the same in a closed position for two horses. Fig. 2 is a perspective view of the same in an open position as it is used when three horses are pulling abreast; and Fig. 3 is a longitudinal horizontal sectional view of the equalizer taken on line *x x*, Fig. 2.

Similar letters of reference indicate corresponding parts in all the figures.

My invention has relation to draft-equalizers; and it consists in the improved construction and combination of parts of the same, as will be hereinafter more fully described and claimed.

In the accompanying drawings, A represents the double-tree, having upon its rear side the brace A', consisting of a metal rod, B, passing over a metal block, B', and having its extremities fastened to the double-tree near either end of the said tree.

Upon the rear side of the double-tree A, near each of its ends, is secured a chafing-plate, C, having fastened rigidly upon it by either extremity a guide-rod, D.

E indicates a metal block of a greater width than the chafing-plate C, and provided with grooves F and G, within which the chafing-plate C and the guide-rod D fit, and with a spring-catch, H, adapted to engage with any one of a series of apertures, I, in the chafing-plate C.

J indicates a metal link, which passes through an aperture in the metal block E, and connects it to a similar metal block, K, sliding between similar chafing-plates, L, and guide-rods M on each of the single-trees N.

O represent metal clips, which are secured one to the clip on the inner end of each sin-

gle-tree, each of the clips O O having a slot, P, through which passes a metal bar or piece, Q, having on either end a hook, R, to which the traces are attached. One end of the piece Q is extended and sharpened to adapt it to enter an aperture, L', in the upwardly-curved end L" of the chafing-plate L. The piece Q is provided upon its upper edge with two or more notches, Q', one at about its center and the other near its outer edge, with which a key, Q", passing through the clip Q, is adapted to engage, for the purpose hereinafter specified.

To adjust my improved draft-equalizer for the use of two horses, the extended sharpened end of each of the pieces Q is inserted within the aperture L' in the upwardly-curved ends of each of the chafing-plates L and fastened securely in that position by means of the keys Q". The sliding blocks E E and K K are then moved so as to bring the single-trees N N together or into their closed position, as shown in Fig. 1 of the drawings, the blocks being held in their adjusted position by their catches H engaging with the apertures I in each of the chafing-plates. The traces for the two horses are then hooked to the hooks on the outer ends of each of the single-trees N N and to the hooks on the outer or free ends of each of the bars or pieces Q Q.

To adjust my improved draft-equalizer in order that three horses may pull abreast, the bars Q Q are moved half-way through the clips O O, and are locked in that position by the keys Q" engaging with their central notches, Q'. The sliding blocks E E and K K are then moved so as to place the single-trees N N at the greatest possible distance from each other, as shown in Fig. 2 of the drawings. The traces for two of the horses are then hooked to the hooks on the outer ends of each of the single-trees N N and to the hooks on the inner end of each of the bars or pieces Q Q, while the traces of the middle horse are hooked to the hooks on the outer ends of each of the bars Q Q.

From the foregoing description, taken in connection with the accompanying drawings, the construction and operation of my improved draft-equalizer will readily be understood without requiring further explanation.

It will be seen that my improved draft-equalizer is simple in construction, and, being de-

void of all complicated mechanism, is not liable to break or get out of order.

Having thus described my invention, I claim and desire to secure by Letters Patent of the 5 United States—

1. In a draft-equalizer of substantially the described construction, the combination of the double-tree A, having brace A', chafing-plates C C, provided with apertures I and guide- 10 rods D D, single-trees N N, having chafing-plates L L, provided with apertures I and guide-rods M M, and movable blocks E E and K K, connected together by links J, and having grooves F G, and spring-catches H, adapted to engage with the apertures I of the chafing-plates, all constructed and arranged to operate substantially in the manner and for the 15 purpose shown and set forth.

2. In a draft-equalizer of substantially the described construction, the combination of the single-trees N N, provided with the slotted clips O O, secured to the single-trees on their inner ends, with the bars Q Q, adapted to be adjustably secured within the slotted clips O O by means of keys Q" Q", and having their inner ends extended to adapt them to enter apertures L' in the upwardly-curved ends of the chafing-plates L L, as and for the purpose shown and set forth.

In testimony that I claim the foregoing as my 30 own I have hereunto affixed my signature in presence of two witnesses.

WILLIAM P. GRANNIS.

Witnesses:

OTIS P. GRANNIS,
FRANK SMITH.
